UNITED STATES PATENT OFFICE.

HARRY S. MILES AND FREDERICK HAAS, OF PHILADELPHIA, PENNSYLVANIA.

BINDING FOR BOOKS.

SPECIFICATION forming part of Letters Patent No. 421,595, dated February 18, 1890.

Application filed April 17, 1889. Serial No. 307,565. (No model.)

To all whom it may concern:

Be it known that we, HARRY S. MILES and FREDERICK HAAS, both citizens of the United States, residing at Philadelphia, in the county 5 of Philadelphia and State of Pennsylvania, have invented certain new and useful Improvements in Bindings for Books; and we do hereby declare the following to be a full, clear, and exact description of the invention, 10 such as will enable others skilled in the art to which it appertains to make and use the same.

Our invention relates to an improvement in 15 bindings for blank-books, and has for its object to increase the flexibility and strength of the binding, and at the same time to enable a book to be bound in such manner as to have a uniform thickness throughout, thereby insuring ease of action in opening and closing 20 the same and its durability in use.

This particular invention is designed as an improvement upon our United States Patent No. 391,810, granted October 30, 1888, wherein certain details of construction and combination of parts are varied or added.

The novel features of our invention are clearly described hereinafter, and pointed out in the appended claims.

Referring to the accompanying drawings, 30 Figure 1 is a perspective view showing our invention as applied to two leaf-sections of a book, and Fig. 2 is an enlarged vertical transverse section showing the relation of the binding to four instead of two leaf-sections.

Like letters of reference refer to like or corresponding parts in both views of the drawings.

Referring to the drawings by letter, and more particularly to Fig. 1, A and B, respectively, represent two sections of leaves (leaf-sections) of a blank-book or other volume, the back of each section A or B being folded or turned at *a* in the usual manner.

C designates a strip of some material, of the 45 desired dimensions and shape, folded in the manner shown in Fig. 1 and more fully described hereinafter. This strip C is of any durable and flexible material—such as muslin or linen—and serves the dual purpose of 50 a connecting medium between the leaf-sections and as a backing for the facing D, which latter is made of thick material—such as

paper—and is secured to and is approximately co-extensive with the outer surface of the sides of the stems or wings *b b'* of each strip 55 C, as will be better understood from the following: The strip C is first formed into an inverted-U shape, and the portions of the stems or wings *b b'* immediately adjacent to their point of union *c* are inserted up between 60 the backs of the two leaf-sections A B. (See Fig. 1.) Then the stem or wing *b*, adjacent to the leaf-section A, is pasted or otherwise secured to the base of the leaf-section A, as shown, thus leaving both the stem *b'* and 65 that portion of stem *b* which projects out below the base of the leaf-sections free. Now, the two leaf-sections A B and the connecting-strip C are sewed together in the manner ordinarily employed, and the free depending 70 stems or wings *b b'* are expanded or opened and folded in the manner shown in Fig. 1. Then the backing D is fastened to the stems *b b'*, so as to conform to the manner in which the latter are folded, as shown clearly in Figs. 75 1 and 2. Each stem or wing *b* or *b'* consists of two portions *d d'*, the portion *d* extending from the point of union *c* to the point *e*, while the portion *d'* extends substantially parallel with *d* from the point *e* upwardly. In other 80 words, each stem or wing *b* or *b'* is folded or turned at *e*, thus forming a U-shaped stem or branch *b* or *b'*.

As shown in Fig. 2, there is one connecting-strip C for every two adjacent leaf-sections, 85 and the several pairs of leaf-sections are secured together serially or successively by the folded extremities of the stems or wings *b b'* of the connecting-strips C C in the following manner: In Fig. 2 the portion *d'* of the stem 90 or wing *b* of one strip C is inserted up intermediately between the portion *d'* of the stem *b'* and the portion *d* of the stem *b* of the other strip C, thus interlocking or dovetailing the two strips C C together. This mode of connection between adjacent strips C C is preserved throughout, and the total number of strips C C are sewed together in the ordinary manner, and are then bound as is usual. The function of the strip C, folded in the manner 100 shown, is to enable leaf-sections to be readily and flexibly joined, and at the same time serves as a support for the thick backing D, which latter is provided in order to render

the thickness of the back or binding equal to that of the leaf-sections.

Having thus fully described our invention, what we claim, and desire to secure by Letters 5 Patent, is—

1. The combination, with two leaf-sections, such as A B, of a flexible connecting-strip, such as C, having expanded stems b b' , divided into two portions d d' and secured to 10 a leaf-section at or near the point of union of said stems b b' , and a backing, such as D, secured to the surface of one side of the strip C and approximately co-extensive with and conforming to the contour of the surface of 15 the expanded stems b b' .
2. The combination, with two connecting-strips, such as C, each secured to a leaf-section and comprising two stems b b' , converg-

ing at c , and each stem b or b' consisting of two portions d d' , of a backing, such as D, 20 secured to each of the said strips C C and conforming in shape and dimensions with that of its strip, the said two strips C C and their attached backings D D being interlocked by the insertion of the portion d' of a stem 25 b of one strip C between the portion d' of stem b' and portion d of stem b of the other strip C.

In testimony whereof we affix our signatures in presence of two witnesses.

HARRY S. MILES.
FREDERICK HAAS.
